TABLE LAMP

Donald R. Kracke, 5620 Whitecliff Drive,
Palos Verdes Peninsula, Calif. 90274

Filed July 27, 1970, Ser. No. 24,142

Term of patent 14 years

Int. Cl. D26—05
U.S. Cl. D48—20

FIG. 1 is a front perspective view of a table lamp, showing my new design;

FIG. 2 is a rear elevational view thereof;

FIG. 3 is a side elevational view taken in the direction of arrow 3 in FIG. 2;

FIG. 4 is a top plan view thereof; and

FIG. 5 is a bottom plan view thereof.

I claim:

The ornamental design for a table lamp, substantially as shown.
